(57) **CLAIM**

The ornamental design for footwear, as shown and
described.

DESCRIPTION

FIG. 1 is a top perspective view of the footwear taken from
a side;

FIG. 2 is a top perspective view taken from an opposite side
thereof;

FIG. 3 is a bottom perspective view thereof;

FIG. 4 is a top view thereof;

FIG. 5 is a bottom view thereof;

FIG. 6 is a side view thereof;

FIG. 7 is an opposite side view thereof;

FIG. 8 is a front view thereof; and,

FIG. 9 is a rear view thereof.

The paired broken lines found on the straps are stitching,
which forms no part of the claimed design. The other broken
line showings in the figures are for the purpose of illustrating
portions of the footwear that also form no part of the claimed
design.
